TOY SAVINGS BANK

Gustav Flexner, Louisville, Ky.

Application July 5, 1951, Serial No. 15,761

Term of patent 14 years

(Cl. D34—11)

To all whom it may concern:

Be it known, that I, Gustav Flexner, a citizen of the United States, and a resident of Louisville, in the county of Jefferson and State of Kentucky, have invented a new, original, and ornamental Design for a Toy Savings Bank, of which the following is a specification, reference being had to the accompanying drawing, forming part thereof.

Figure 1 is a perspective view of a toy savings bank embodying my new design;

Figure 2 is a top view of Figure 1;

Figure 3 is a front elevation view; and

Figure 4 is a cross section taken on line 4—4 of Figure 3.

The rear wall is substantially flat.

I claim:

The ornamental design for a toy savings bank, as shown and described.

GUSTAV FLEXNER.
